UNITED STATES PATENT OFFICE.

FREDERICK H. WILLCOX, OF CHICAGO, ILLINOIS, ASSIGNOR TO FREYN ENGINEERING COMPANY, OF CHICAGO, ILLINOIS, A CORPORATION OF MAINE.

BLAST-FURNACE CONSTRUCTION.

Application filed May 17, 1924. Serial No. 713,966.

This invention relates to new and improved blast furnace construction and more particularly to a skip incline adapted for use with blast furnaces and constructed independently 60 of the bell supporting structure.

Skip inclines as at present generally constructed are anchored at their lower ends and supported at a median point by an A-frame. The upper end of the skip incline is a cantilever and also supports the bells which close the top of the blast furnace and control the distribution of the furnace charge. It is important for the proper introduction and distribution of the furnace charge that the bell 65 be properly centered in the top of the furnace. With a cantilever skip incline and bell support independent of the furnace, it will be apparent that any variation of the location of the bell will be independent of variation 70 of the associated portions of the furnace top.

As a rule, the A-frame which supports the median portion of the skip incline is located on the furnace foundation. Therefore, if the 75 furnace foundation settled any amount, the A-frame will settle a corresponding amount. However, the upper end of the skip incline cantilever will move a greatly increased amount due to the multiplication of the movement. For example, if the A-frame were 80 about midway of the skip incline, the upper end of the incline would move approximately twice the vertical displacement of the A-frame and also have a material lateral movement.

Further, the skip incline cantilever supporting the bell has a natural sag or deflection due to its load. There will be an initial permanent deflection during the first few weeks of operation. Further, there will be additional deflection which will be dependent in amount upon the weight of material in the skip buckets carried to the top of the skip incline and dumped, and also due to the weight 85 of material held upon the bell. These latter causes result in a constant variation of location of the bells. The initial deflection can be taken up by adjustment but these other variations cannot be compensated for and may 90 themselves lead to confusion when the location of the bell is checked to correct the permanent deflection.

An additional source of variation in the location of the bell lies in the expansion and contraction of the skip incline due to heat.

During summer months, skip inclines have been found to vary in length as much as two inches between night time and day time. In the day time the hot sun-light upon the black structure causes the latter to absorb enough 60 heat to expand sufficiently to throw the bells materially out of position. Further, when one side of the furnace itself becomes hotter than the other, or when the furnace settles a little unevenly, the ring and hopper are moved 65 independently of the position of the bells when the latter are hung from the top of the skip incline.

It is an object of the present invention to provide a skip incline and bell supporting construction in which the bells are supported independently of the skip incline.

It is a further object to provide a construction in which the bells are so supported relative to the blast furnace top as to maintain 75 substantially fixed relation therewith.

Other and further objects will appear as the description proceeds.

I have illustrated a preferred embodiment of my invention in the accompanying drawings, in which—

Figure 1 is a fragmentary elevation partly in section showing my improved construction applied to a furnace top;

Figure 2 is a view of Figure 1 as seen from 85 the left;

Figure 3 is a plan view of the construction shown in Figure 1; and

Figure 4 is a view on a smaller scale showing the relation of the skip incline to the blast 90 furnace.

Referring first to Figure 4, the blast furnace 11 is supported upon the foundation 12 and is provided at its upper end with the frame 13 supporting the bell operating levers 15 and 16, the frame being supported upon the furnace shell. The skip incline 17 is supported at its lower end upon foundation 18 and is supported at an intermediate point by the A-frame 19 which frame is supported 100 upon the furnace foundation 12. The upper end 20 of the skip incline is of cantilever construction. The bell operating cables 21 and 22 pass over idler pulleys 23 and 24 carried by the skip incline and down to the operation house 25.

Referring now to the detailed construction as shown in Figures 1, 2 and 3, the top of the furnace shell supports the hopper 26, the lower end of which is closed by the large 110

bell 27. This bell 27 is carried upon stem 28 which is connected by chain 29 to the end 30 of the rock lever 15 which is pivoted upon the cross shaft 32. The shaft 32 is supported 5 on the cross frame 33 which latter is carried by the frame 34 from the top of the furnace shell.

The small bell 35 is carried by the tubular stem 36, which latter surrounds the stem 28 10 of the large bell. The small bell 35 closes the lower end of the receiving hopper 37.

As best shown in Figure 2, the upper end of the tubular stem 36 is connected to the yoke 38 which latter is suspended from the pair 15 of rockers 16 by means of rods 39 and chains 40. This rock lever 16 is also supported on the pivot shaft 32 which latter is supported from the furnace top as above described. The upper end 20 of the skip incline carries 20 the platform 41 upon which are supported the pulleys 42 over which pass the cables 43 which serve to draw the skips 44 to the top of the incline.

In the construction above described, the 25 large and small bells 27 and 35 are supported entirely independently of the skip incline.

Any movement of the upper end of the furnace will cause a similar movement of the bells inasmuch as they are supported directly

from the furnace. The location of the bells 30 will be entirely independent of the vibration of the skip car travel and of deflection and side thrust resulting from weight of the skip cars and their charges. The weight of the charge resting on the bells will exert a direct 35 downward pull on the construction and will cause no material lateral movement such as is the case when the weight is applied at the end of an angularly extending cantilever as in older constructions.

The detailed structure shown is to be understood as illustrative only as I contemplate such changes and modifications to meet the varying conditions of different installations, as may come within the spirit and scope of 40 the appended claim.

I claim:

Blast furnace construction comprising a bell supporting frame carried by the furnace structure, a skip incline structure supported independently of the furnace, and idler pulleys carried by the skip incline coacting with bell operating cables whereby the lateral thrust of such cables is received by the independent skip incline structure.

Signed at Chicago, Illinois, this 14th day of May, 1924.

FREDERICK H. WILLCOX.
